(57) **CLAIM**

The ornamental design for a fishing lure retrieval device, as shown and described.

DESCRIPTION

FIG. 1 is a front, perspective view of a preferred embodiment of the present invention;

FIG. 2 is an enlarged, fragmentary, front, perspective view thereof, particularly showing an eyelet screw mounted in the front end thereof;

FIG. 3 is a rear perspective view thereof;

FIG. 4 is a right side elevational view thereof, the left side being a mirror or image thereof;

FIG. 5 is a top plan view thereof, the bottom plan view being a mirror image thereof;

FIG. 6 is a front elevational view thereof;

FIG. 7 is a rear elevational view thereof;

FIG. 8 is a front, perspective view of a fishing lure retrieval device comprising a modified or alternative embodiment of the present invention;

FIG. 9 is an enlarged, fragmentary, front, perspective view thereof, particularly showing a clip mounted in the front end thereof;

FIG. 10 is a rear perspective view thereof;

FIG. 11 is a right side elevational view thereof, the left side being a mirror or image thereof;

FIG. 12 is a top plan view thereof, the bottom plan view being a mirror image thereof;

FIG. 13 is a front elevational view thereof; and,

FIG. 14 is a rear elevational view thereof.
